(57) **CLAIM**

The ornamental design for an intraoral orthosis, as shown and described.

DESCRIPTION

FIG. 1 is an exploded front perspective view of an intraoral orthosis, showing my/our new design;
FIG. 2 is an exploded front elevation view thereof;
FIG. 3 is an exploded rear elevation view thereof;
FIG. 4 is an exploded right elevation view thereof;
FIG. 5 is an exploded left elevation view thereof;
FIG. 6 is an exploded top plan view thereof;
FIG. 7 is an exploded bottom plan view thereof;
FIG. 8 is a front perspective view thereof;
FIG. 9 is a front elevation view thereof;
FIG. 10 is a rear elevation view thereof;
FIG. 11 is a left elevation view thereof;
FIG. 12 is a top plan view thereof; and,
FIG. 13 is a bottom plan view thereof.

The broken line portion of the figures is included to show unclaimed subject matter only and forms no part of the claimed design.
